DISPLAY CABINET FOR BOTTLES OR THE LIKE

Samuel Eisenberg, Washington, D.C.

Application May 27, 1958, Serial No. 51,105

Term of patent 14 years

(Cl. D80—11)

The figure is a front perspective view of a display cabinet for bottles or the like showing my new design.

The back of the display cabinet is substantially plain and the side not shown is like the side shown.

The broken line showing of the bottles in the drawing is for illustrative purposes only.

I claim:

The ornamental design for a display cabinet for bottles or the like, as shown and described.
